UNITED STATES PATENT OFFICE.

GEORGES LACQUIT, OF PUTEAUX, FRANCE.

AIR BOTTLE FOR CYCLES.

Application filed October 10, 1925, Serial No. 61,828, and in France October 21, 1924.

Bottles containing compressed air for instantaneously inflating the inner tubes of bicycles are already known. The devices used for this purpose up to the present time are generally provided with a centre punch which is operated by means of a brace device located at the end of the apparatus, the fitting adapted to be applied to the valve of the machine being arranged at the side of the body of the bottle. With such an apparatus it is necessary, when holding the body of the bottle with one hand, to pass the other hand to the other side of the wheel for the purpose of operating the punch. This operation is extremely awkward and does not permit of holding the fitting pressed efficiently upon the valve thus causing a considerable leakage of the air contained in the bottle.

The present invention has for its subject an air bottle which can be operated easily and which prevents losses of air. This bottle, which constitutes a new industrial product, is more particularly characterized by the combination, with the body of the bottle, of a closing device screwed upon the latter and of which the operation is effected by holding it with one hand and turning the bottle slightly with the other hand, the two hands being placed on the same side in relation to the wheel. At the outer end of the said closing device there is screwed a self-adapting fitting directed at right angles to the axis of the bottle.

The invention also has for its subject various forms of construction of the new industrial product in question.

Figure 1 is a view in elevation of a device which is operated by holding in the hand an external sleeve secured to the closing device.

Figure 2 is a vertical section corresponding to Figure 1.

Figure 3 is a modification in which the operation is effected by means of a milled head which may be engaged between the thumb and the first finger.

Figure 4 is a partial vertical section corresponding to Figure 3.

Figures 5 and 6 show in elevation and plan respectively detail views of the conical closing member.

Figure 7 shows an external view in elevation of a third form of construction.

Figure 8 shows partly in elevation, partly in cross section the same construction. 55

Figure 9 shows in elevation an external view of a fourth form of construction. 60

Figure 10 shows in elevation an external view of a fifth form of construction, and 65

Figure 11 shows a longitudinal section of the last mentioned form of construction.

As shown in Figures 1 and 2 the apparatus comprises the body 1 of the bottle of which the upper end is provided with an external screw thread 2 on which is screwed a sleeve 3 from which extends an externally threaded sleeve 4. The sleeve 3 is internally threaded so as to receive a tube 5 at the end of which is screwed the self-adapting fitting 6 directed at right angles to the axis of the bottle. In the interior of the sleeve 3 is disposed a metal disc 7 of which the central portion is provided with a conical projection 8 of which the point is adapted to close the outlet orifice 9 of the bottle. The disc 7 of which the diameter is slightly less than the internal diameter of the sleeve 3, is provided with a diametral groove 10 extending through the whole thickness thereof. A rubber washer 11 forced into the sleeve 3 holds the disc 7 against the bottom of the sleeve 3. On the extension 4 of the latter is loosely mounted a sleeve 12 which partly covers the body of the bottle and of which the height is sufficiently large to enable it to be gripped by the hand. A nut 13 which is screwed on the part 4 enables the sleeve 12 to be secured to the sleeve 3 which latter is also provided with a projection 14 which is adapted to engage with an opening 15 provided in the upper part of the sleeve 12. 70 75 80 85 90

The operation of the device is as follows:— 95

When it is desired to use the apparatus for inflating the inner tube of a bicycle, the body 1 of the bottle is gripped in the right hand and the self-adapting fitting 6 is pressed against the valve. The sleeve 12 is 100 then gripped by the left hand and the body of the bottle is slightly unscrewed so as to expose the passage 9 and allow the air to pass into the inner tube through the passages 10 and 5 and the fitting 6. It will be seen that the two hands can serve to hold the self-adapting fitting in position on the valve which avoids any risks of leakage 105

due to accidental separation of these two parts. As it is not necessary to place the hands on opposite sides of the wheel the cycle may be placed against a wall and the wheel can be held against the ground by the foot. As soon as the inner tube has been sufficiently inflated, a slight turning of the body of the bottle brings the point of the cone 8 into the passage 9 and instantly stops the passage of air.

The device shown in Figures 3 and 4 differs from that shown in Figures 1 and 2 by reason of the fact that the sleeve 12 is omitted and the sleeve 3 is gripped directly between the thumb and first finger, for which purpose the exterior of the sleeve 3 is milled.

It will be understood that the invention is not limited to the forms of construction which have been described and these are capable of being modified in detail without varying the scope of the invention by reason of these modifications.

For example, the conical closing device 8 may be formed integral with the bottom of the sleeve 3 of which it then forms an internal extension a suitable passage being provided so as to form communication between the passage 5 and the space contained in the interior of the rubber washer 11.

As will be seen in Figures 7 and 8, this form of construction is characterized by the combination with the principal body 1, which constitutes the container for the compressed air to be used, of an operating handle 16 adapted to pivot on a pivot 17 provided at the end 4 of the body 1.

The upper part 19 of the handle 16 forms a kind of cap in the central portion of which is provided an opening 20 through which passes the outer end of a member 21 whose other end 22 slides in the interior of a cylindrical passage 23 provided in the bottom 18 of the body 1. The outer end 24 of the member 21 is screw threaded and the self-adapting fitting 6 may be screwed thereon. At the end of the internal portion thereof, the said member 21 is provided with a conical extension 8 forming a kind of pointed shell adapted, when it is pressed against the opening 9 provided in the bottom of the body 1, to close this opening.

Along the axis of the member 21 there is provided a passage 5 which communicates with the exterior adjacent the wall of the shell 8 by auxiliary passages 25.

On the outer surface of the member 21 there is provided a circular shoulder 26 on which bears the edge 27 of the opening 20 provided in the hood of the handle 16.

Below the lower shoulder 28 of the member 21 and the bottom 18 of the body 1 there is disposed a rubber ring 29 which produces the fluid tightness of the apparatus, during its operation.

A spring 30 located between the inner sur-

face of the handle 16 and the outer surface of the body 1 of the apparatus acts upon the handle 16 in such a manner as to cause the point of the shell 8 to bear against the opening 9 in the bottom 18 of the body 1.

The operation of the apparatus is very simple. After the self-adapting fitting 6 has been placed against the valve of the inner tube which is to be inflated it suffices to press upon the handle 16 as to cause it to approach the body 1 by turning on the pivot 17.

During this movement the edge 27 of the opening 20 in the hood moves a shoulder 26 of the member 21 and consequently enables this member to move under the action of the compressed air contained in the body 1.

When the handle 16 is released, the spring 30 tends to turn the handle in the opposite direction about the pivot 17 and consequently returns the shell 8 against the edges of the orifice 9 thus closing the latter. The method of construction shown in Figure 9 is exactly similar in construction to the arrangement shown in Figure 3 as regards the internal arrangements of the elements.

This construction only differing in the external members, the sleeve 3 with three milled rings is replaced, for the convenience of operation, by a member 31 provided with a roughened operating lug 32.

In the construction shown in Figures 10 and 11, the sleeve which enables the opening device to be actuated and for closing the bottom is arranged at the lower end of the latter.

The closing member 33 is provided at the end of a rod 34 of which the part adjacent the member 33 is screw threaded and may be screwed into a sleeve 35 formed integral with the bottom of the body 1.

The rod 34 which extends along the whole length of the bottle engages at its lower end 36, which is suitably flattened, with a groove 37 provided centrally in a member 38 of which the end 39 is secured to the operating sleeve 41 by a nut 40.

The member 38 is also provided with a shoulder 42 which, in combination with the end of a nut 43 screwed into the bottom 44 of the body and with a resilient washer 45 ensures the fluid tightness of the whole device.

The washer 46 disposed between the front face of the nut 43 and the bottom 44 of the body ensures the fluid tightness of the closure.

Having thus described my invention, what I claim as new and desire to secure by Letters Patent is:—

1. A compressed air bottle for inflating the inner tubes of cycles comprising a receptacle containing compressed air and having an outlet orifice therein, a screw threaded portion at one end of said receptacle, a screw threaded cap engaging with said screw

threaded portion, a valve member mounted in said cap and adapted to co-operate with said outlet orifice, said valve member consisting of a disc with a diametral slot therein and 5 a conical portion, a resilient washer forced into said screw threaded cap and adapted to hold the disc in engagement with the bottom of said cap, a tubular extension formed on said cap, and a fitting mounted in said 10 tubular extension and adapted to be connected to the inlet valve of the inner tube.

2. A compressed air bottle for inflating the inner tubes of cycles comprising a receptacle containing compressed air and having 15 an outlet orifice therein, a screw threaded portion at one end of said receptacle, a screw threaded cap engaging with said screw threaded portion, a valve member mounted in said cap and adapted to co-operate with

said outlet orifice, said valve member consisting of a disc with a diametral slot therein and a conical portion, a resilient washer forced into said screw threaded cap and adapted to hold the disc in engagement with the bottom of said cap, a tubular extension 20 formed on said cap, and a fitting mounted in said tubular extension and adapted to be connected to the inlet valve of the inner tube, a projection on said cap, a sleeve fitted over 25 said cap and extending partly over the receptacle, said sleeve having an opening therein adapted to receive said projection, and a nut adapted to screw on the tubular extension for the purpose of securing the 30 sleeve to the cap. 35

In testimony whereof I have signed my name to this specification.

GEORGES LACQUIT.
